UNITED STATES PATENT OFFICE.

WILLIAM T. MERSEREAU, OF SOUTH ORANGE, NEW JERSEY.

DESIGN FOR A BADGE.

SPECIFICATION forming part of Design No. 18,529, dated August 14, 1888.

Application filed June 8, 1888. Serial No. 276,516. Term of patent 3½ years.

To all whom it may concern:

Be it known that I, WILLIAM T. MERSEREAU, a citizen of the United States, residing at South Orange, Essex county, in the State of New Jersey, have invented and produced a new and original Design for a Badge or Banneret, adapted in this present instance for a campaign emblem, of which the following is a specification, reference being had to the accompanying drawing, forming a part thereof.

The figure represents a face view of my newly-designed badge or banneret.

In the accompanying drawing, A represents the body of the badge, of a shield-shaped form, as shown, surrounded by a beaded marginal band or border, and is divided into an upper and a lower panel by a beaded band ex-

tending across the face of the badge near the top thereof. In the lower panel the outline of the United States and Mexico is traced thereon, substantially as shown.

I claim—

The design for a badge or banneret herein shown and described, the same consisting of a shield-shaped body surrounded by a marginal beaded band or border and divided into an upper and lower panel by a beaded band, the outline of the United States and Mexico being traced in the lower panel, substantially as shown.

WILLIAM T. MERSEREAU.
